UNITED STATES PATENT OFFICE.

ALBERT J. DOTY, OF PHILADELPHIA, PENNSYLVANIA, ASSIGNOR, BY MESNE ASSIGNMENTS, TO THE GOODWIN GAS STOVE AND METER COMPANY, OF SAME PLACE.

MULTIPLE HEATING GAS-BURNER.

SPECIFICATION forming part of Letters Patent No. 411,648, dated September 24, 1889.

Application filed June 6, 1887. Serial No. 240,422. (No model.)

To all whom it may concern:

Be it known that I, ALBERT J. DOTY, of Philadelphia, in the county of Philadelphia and State of Pennsylvania, have invented a new and Improved Multiple Heating Gas-Burner, of which the following is a specification, reference being had to the annexed drawings, forming a part thereof, in which—

Figure 1 is a plan view of one form of my improved multiple burner. Fig. 2 is a side elevation, partly in section, taken on line xx in Fig. 1. Fig. 3 is a horizontal section taken on line yy in Fig. 2 of the central part of the burner. Fig. 4 is a partial plan view of a ring-burner constructed according to my improvement, and Fig. 5 is a partial plan view of a multiple ring-burner constructed according to my improvement.

Similar letters of reference indicate corresponding parts in all the views.

Where a large flame-surface is desired, it is impracticable to secure it by means of a large perforated ring or a series of perforated rings receiving the combustible mixture in one side of the rings, as the friction of the gas in its passage from the point of supply to the part of the ring remote from the said point causes an injurious diminution of the gas-pressure at the remote point.

The object of my invention is to provide a gas-burner in which the gas will be evenly distributed to all parts thereof, so as to secure uniform heating and a uniform combustion of the gas.

My invention consists in a series of radial arms having gas-burning orifices at their extremities, and provided at their intersection with a gas-supply nozzle having as many gas-orifices as there are arms, and a central air-supply common to all the arms.

In the simplest form of my improved burner the hollow arms A radiate from a common center B and are provided at their extremities with upwardly-turned nozzles C, from which the combustible mixture issues. At the intersection of the said arms is supported the gas-nozzle D, having orifices a corresponding in number and position with the hollow arms A. In the present case the arms are formed

integrally in one casting, and are approximately semicircular in cross-section, and the open side of the said arms is closed by a

cross-shaped plate E, having a central aperture e larger than the gas-nozzle D. The plate E is held in place by bolts f , and the gas-nozzle D is connected with the gas-supply pipe F.

When it is desired to employ an annular burner, the ring G is formed upon the ends of the arms A, and provided with holes g for the escape of the combustible mixture.

In Fig. 5 is shown a burner in which each arm A is provided with a small perforated ring G'. In these cases the arrangement of the gas-nozzle and air-opening is the same as that shown in Figs. 1, 2, and 3.

By means of my improvement the gas is projected directly to the point of use without undue loss by friction, and as a consequence every part of the flame of the burner is uniform.

Having thus fully described my invention, I claim as new and desire to secure by Letters Patent—

1. A multiple gas-burner consisting of a central chamber B, having a series of hollow arms A radiating therefrom, provided at their ends with gas-jets, a gas-nozzle D, secured within said central chamber B, provided with separate gas jets or orifices a , delivering gas into each of said radial arms, said chamber B being perforated at its base with an annular or central aperture e , surrounding the gas-nozzle D, said parts being constructed, combined, and arranged substantially as set forth. 85

2. In a multiple gas-burner, the combination of the following parts, viz: a series of hollow arms A, cast in approximately semi-circular form and integrally with the central chamber B, a base-plate for both of the same, 90 consisting of the cross-shaped plate E, having an annular central air-aperture e , a central gas-nozzle D, provided with gas-orifices a and secured within said chamber B, and projecting downward through the center of the aperture e and communicating with the gas-supply pipe F, said parts being constructed, combined, and arranged substantially as set forth. 95

ALBERT J. DOTY.
